UNITED STATES PATENT OFFICE.

RUSSEL G. WOODWARD, OF WAUKEGAN, ILLINOIS, ASSIGNOR TO UNION
SPECIAL SEWING MACHINE CO., OF CHICAGO, ILLINOIS.

DESIGN FOR A SEWING-MACHINE NEEDLE-LEVER.

SPECIFICATION forming part of Design No. 34,728, dated July 2, 1901.

Application filed June 6, 1901. Serial No. 63,465. Term of patent 14 years.

To all whom it may concern:

Be it known that I, RUSSEL G. WOODWARD, a citizen of the United States, residing at Waukegan, in the county of Lake, State of Illinois, 5 have invented a certain new and original Design for a Sewing-Machine Needle-Lever, of which the following is a description, reference being had to the accompanying drawing and to the letters of reference marked thereon.

My invention relates to a new and original design for a needle-lever for sewing-machines; and it consists in the needle-lever of the shape and configuration hereinafter referred to.

The accompanying drawing represents in 5 perspective a needle-lever embodying my design.

A represents as a whole the needle-lever, having the forwardly-projecting perforated end *a* and the downward extension *b*, the under side of the needle-lever from the forward end to the lower end of the extension *b* being formed on a continuous convex curve. Said

needle-lever is narrow at its forward end and gradually widens to the point *B*, the upper edge being formed on a curve, and at its widest point is provided with the transverse horizontal projecting member *D*, formed with the groove *e* and split, as shown at *f*. The needle-lever has also the horizontal tubular projections *c d*. 25

The leading feature of the design is the needle-lever of the shape shown.

Having thus described my invention, what I claim as new, and desire to secure by Letters Patent, is—

The design for a sewing-machine needle-lever; substantially as shown and described.

In testimony whereof I affix my signature in presence of two witnesses.

RUSSEL G. WOODWARD.
